UNITED STATES PATENT OFFICE.

EMMANUEL T. RICHERT, OF CANTON, OHIO.

DESIGN FOR A TOY BALLOON.

58,109.

Specification for Design.

Patented June 7, 1921.

Application filed January 31, 1921. Serial No. 441,438. Term of patent 14 years.

To all whom it may concern:

Be it known that I, EMMANUEL T. RICHERT, a citizen of the United States, residing at Canton, in the county of Stark and State of Ohio, have invented a new, original, and ornamental Design for Toy Balloons, of which the following is a specification, reference being had to the accompanying drawing, forming part thereof.

Figure 1 is an elevation of a toy sausage

balloon or a toy squawker sausage balloon in a condition ready to be inflated.

Fig. 2 is a bottom plan view of the same. Referring to the drawing, 1, 2 and 3 indicate zones of suitable contrasting colors.

I claim:

The ornamental design for a toy balloon as shown.
